UNITED STATES PATENT OFFICE.

HENRY HOWSON, JR., OF PHILADELPHIA, PENNSYLVANIA.

TELEGRAPH RELAY AND SOUNDER.

SPECIFICATION forming part of Letters Patent No. 245,500, dated August 9, 1881.

Application filed June 20, 1881. (No model.)

To all whom it may concern:

Be it known that I, HENRY HOWSON, Jr., a citizen of the United States, residing in Philadelphia, Pennsylvania, have invented certain 5 Improvements in Telegraph Relays and Sounders, of which the following is a specification.

My invention relates to certain improvements in the construction of the telegraphic instruments known as "Morse" sounders and relays, 10 the object of my invention being to provide a simple means of adjustment of the electro-magnet in relation to the armature.

In the accompanying drawings, Figure 1 is 15 a perspective view of my improved telegraphic instrument; Fig. 2, a side view with the frame in section; Fig. 3, a rear view; and Fig. 4, a view of a modification of the instrument when adapted to be used as a relay.

Referring to Figs. 1, 2, and 3, which show 20 the instrument when adapted to be used as a sounder, A represents the armature, and M M the electro-magnet. The electro-magnet in this instance is shown as composed of two coils or spools connected together at their bases by the 25 cross-piece m. This cross-piece is provided with extensions m', which form pivots adapted to corresponding recesses or notches in lugs d on the frame D of the instrument. The outer ends of these extension-pieces are threaded for the 30 reception of screw-nuts d', by screwing which against washers in contact with the lugs d the magnet may be firmly secured in any position to which it may be adjusted, Fig. 2. The terminal wires of the coils of the electro-magnet 35 are connected in the usual manner to suitable binding-stops, b b, on the base B.

The armature-lever has its conical pivot-points supported in screws e e mounted in the yoke E on the upper part of the frame, and 40 the extent of the vibrating movement of the armature is limited by the fixed stops a a' on the base. The armature is moved in one direction by the attraction of the electro-magnet and in the other by a push-spring, a², or 45 in some cases the return movement of the armature, when released by the electro-magnet, may be accomplished simply by the gravity of the armature-lever, the positions of the stops a a' in relation to a vertical line through the 50 pivoting-point of the armature being properly arranged for that purpose.

The armature proper, instead of being a nar-

row strip of metal, as usual, is in the form of a plate of considerable width, and is curved to correspond with the arc described by the extremities of the poles of the electro-magnet in moving the latter from one extreme point of adjustment to the other, as indicated by dotted lines in Fig. 2. But the curve or arc of the inner face of the armature, while preferably of 55 nearly the same radius as the arc described by the extremities of the poles of the electro-magnet, is not drawn from the same center, but from a point eccentric to the pivoting point of the electro-magnet when the end of the armature bears against the stop a', so that when the electro-magnet is adjusted to the highest position indicated by dotted lines in Fig. 2, with its poles nearest the fulcrum of the armature-lever, the said poles will be nearest the 60 face of the armature; but as the poles of the magnet are adjusted farther away from the fulcrum, the distance between the said poles and that portion of the face of the armature directly opposite will be proportionately greater. By 65 this means the distance between the poles of the electro-magnet and the face of the armature can be readily regulated to free the armature from the effects of the residual magnetism in the magnet, and by the same adjustment 70 the distance of the point of attraction from the fulcrum of the lever is proportionately regulated. Thus an increase in the distance between the poles and the face of the armature is compensated for by an increase in the distance of the point of attraction from the 75 fulcrum, the adjustment being made, of course, without affecting the circuit-connections in any way. In the modification shown in Fig. 4 this 80 double adjustment is obtained in a similar manner by causing the electro-magnet to move over an inclined plane.

The under side of a bar or plate, m, on the base of the spools M is beveled and adapted to guides on block n, having a correspondingly- 85 inclined face. An adjusting screw-rod, m², turning in bearings on the block n, passes through a threaded opening in the bar or a projection on the bar m. By turning this regulating-screw the electro-magnet is adjusted 90 so as to bring its poles nearer to or farther from the face of the armature A, and at the same time bring the point of attraction nearer to or farther from the fulcrum of the armature- 95

lever, the armature in this case, as in the instrument shown in Fig. 1, being elongated in respect to the poles in the direction of the line of adjustment.

5 In order to obtain the adjustment of the magnets in respect to the fulcrum of the armature-lever without reference to and independently of the adjustment toward and from the face of the armature proper, the block n may be adapted to longitudinal guides on the base B , and be provided with a regulating-screw, n' , by which the block and electro-magnet may be adjusted in a longitudinal line with the armature-lever without changing the distance between the poles and the armature when the latter is under the attractive influence of the magnet.

The armature-lever in this case is shown as acted on by a push-spring, a^2 , and as the instrument is illustrated in this view to act as a relay the extent of vibration is more limited than in the case of the sounder, and the inner striking-face of the armature-lever is insulated, and has a projecting platinum tip to strike against a corresponding tip on the stop a' . These points are electrically connected with the binding-posts b' for the local circuit.

It will be understood that the instrument shown in Figs. 1, 2, and 3 may be constructed so that the magnet may be adjusted, as in Fig. 4, in respect to the fulcrum of the armature-lever, without changing the distance between the poles of the magnet and the face of the armature by mounting the bearings for the extension-pivots m' on guides and providing them with adjusting-screws, as in the case of the block n , Fig. 4.

I claim as my invention—

1. A relay or sounder in which a vibrating armature, elongated in respect to the poles of the electro-magnet, is combined with an electro-magnet having its poles adjustable from and toward the fulcrum of the armature-lever without breaking the circuit, all substantially as described. 40

2. A relay or sounder in which a vibrating armature is combined with an electro-magnet adjustable from and toward the fulcrum of the armature-lever, and from and toward the face of the armature, whereby, when the magnet is adjusted to increase the distance between the poles and the armature, the same movement will increase the distance between the point of attraction and the fulcrum of the lever. 45

3. In a relay or sounder, the combination of a vibrating armature having a widened curved face with an electro-magnet adjustable on a pivot, and devices, substantially as described, for retaining the magnet in any position to which it may be adjusted in relation to the fulcrum of the armature. 55

4. In a relay or sounder, the combination of an electro-magnet adjustable on a pivot with an armature having a curved face eccentric to the arc described by the poles of the electro-magnet when the latter is adjusted on its pivot, 60 all substantially as and for the purpose set forth.

In testimony whereof I have signed my name to this specification in the presence of two subscribing witnesses.

HENRY HOWSON, JR.
